UNITED STATES PATENT OFFICE.

WILLIAM BENJAMIN SMITH, OF ATLANTA, GEORGIA.

GRAIN-CRADLE.

SPECIFICATION forming part of Letters Patent No. 352,372, dated November 9, 1886.

Application filed October 23, 1885. Serial No. 180,706. (No model.)

To all whom it may concern:

Be it known that I, WILLIAM BENJAMIN SMITH, a citizen of the United States, residing at Atlanta, in the county of Fulton and State 5 of Georgia, have invented new and useful Improvements in Grain-Cradles, of which the following is a specification.

My invention relates to an improvement in grain-cradles.

10 The object is to provide a metal cradle of such construction and proportions that it will be lighter and more durable than those hitherto constructed.

A further object is to provide a cradle which 15 will not hang in the grain or in vines, even when the grain is fallen down.

A further object is to provide a cradle which may be manufactured at less cost, be more easily repaired, and adjusted to the blade and 20 handle than those hitherto constructed.

With these ends in view my invention consists in certain features of construction and combinations of parts, as will be hereinafter described, and pointed out in the claims.

25 In the accompanying drawings, Figure 1 is a view of my improved cradle in perspective. Fig. 2 is a detached view of one of the cross-rods and tubes for securing the fingers in position. Fig. 3 is a view of one of the fingers, 30 and Fig. 4 is a detached enlarged view of the bar for securing the ends of the fingers to the handle. Figs. 5 and 6 represent cross-sections through lines *x x* and *y y*, respectively, of plate *g*.

35 Letters Patent No. 322,885, entitled "grain-cradles," were granted to me on July 21, 1885, and the present invention relates particularly to improvements upon the construction there shown and described.

40 *a a* represent tubes made of sheet iron, tin, or any light metal, having transverse slots *j j* cut in them to admit the metallic fingers *f*. One of the tubes *a* is located at or near the point of the blade, and the other a short distance from the heel of the blade, and both 45 extend transversely, or nearly so, to the blade. Rods *b* extend through the tubes *a*, and are bent at right angles at their ends next the blade, and provided with eyes *K*, through 50 which they are bolted to the blade by bolts *m*, provided with draw-nuts. The ends of the rods *b* which project through the opposite

ends of the tubes *a* extend through the upper rail or border finger, *n*, of the cradle, and the said rail or finger is secured on the rods *b* in 55 contact with the ends of the tubes *a* by means of nuts working on the threaded ends of the rods.

g is a bar made of light sheet metal having one edge turned to give it the required strength, 60 and provided with a series of holes for the ends of the fingers to hook into. The bar *g* is secured to the lower end of the handle or snath by a bolt, *g'*, and at its opposite end to a bracket or stay, *h*. The latter consists of a piece of sheet metal 65 folded over at right angles and secured to the handle by screws *l l*, one located near its end and one extending through the fold. The bracket or stay *h* is provided with a series of perforations, *l*, through which the end of the 70 bar *g* may be secured at different distances from the handle, for the purpose which will hereinafter appear.

The fingers *f* consist of metallic rods or tubes having their points *f'* bent in the form of an 75 eye or hook, and adapted to embrace the rod *b* within the tube *a* at the point of the blade; thence they extend to the rod *b* within the other tube *a*, where they are bent to form an eye or loop, *f''*, which is adapted to embrace 80 the rod *b*, the finger entering and coming out of the slot *j*, and thence the finger extends to the bar *g*, in one of the perforations of which it is hooked. The upper rail or border finger, *n*, projects past the end of the heel-tube *a*, and 85 from its extreme end a brace, *e*, leads to the bracket *h*, to which it is secured, preferably by means of the same bolt, *h'*, which secures the bar *g* to the bracket. The brace *e* is secured to the end of rail or border finger *n* by means 90 of a pair of adjusting-nuts, *i*, which work on its threaded end, and serve to regulate the angle of the rail *n* with respect to the handle or snath, and hence the set of the point of the cradle. A stay-rod, *d*, extends from the rail 95 or finger *n* at the end of the rod *b* to the lower end of the handle or snath, and is secured to the latter, preferably by means of the same bolt which secures the lower end of the bar *g* to the handle. It is secured to the rod *b* by the nut 100 *b'*, which secures the rail *n* thereto. A third brace, *e*, extends from the heel end of the rail or finger *n* to the rod *b* near its blade end, and is provided with an eye or loop at each end,

which embrace, respectively, the rod *c* and the rod *b* within the tube, entering the tube *a* through one of the slots *j*. A fourth stay, *o*, extends from the rail or finger *n* at the end of the rod *b* to the upper end of the bar *g*, and is secured conveniently by the bolts *b'* and *h'*.

By moving the upper end of the bar *g* away from and toward the handle or snath by means of the perforations *l*' and bolt *h'* the upper part of the cradle is made to assume the desired position relatively to the blade.

The bolts *m* *m*, which secure the rods *b* to the blade, serve to secure the blade firmly to the cradle, rendering it stiff and capable of passing through extremely heavy grain without warping or giving way.

Having fully described my invention, what I claim as new, and desire to secure by Letters Patent, is—

20 1. In a grain-cradle, the combination, with the blade and handle or snath, of a bar secured to the handle or snath in swinging adjustment, and a series of fingers secured to the blade and the swinging bar, and adapted to be 25 adjusted by the adjustment of the bar, substantially as set forth.

2. In a grain-cradle, the combination, with the handle or snath and the blade, of the movable bar *g*, fingers *f*, bracket or stay *h*, 30 and means for fastening, substantially as set forth.

3. In a grain-cradle, the combination, with the tubes *a*, having transverse slots formed therein, of the fingers *f*, adapted to enter the 35 slots, and the rods *b*, for securing the fingers in the tube, substantially as set forth.

4. In a grain-cradle, the combination, with the handle or snath, a bar adjustably secured thereto, and rods extending longitudinally 40 through slotted tubes located transversely to the blade, of fingers attached to the adjustable bar and held in position by the rods within the tubes, substantially as set forth.

5. In a grain-cradle, the combination, with the upper rail or border finger, the handle, 45 and the blade, of the slotted tubes *a* *a*, fingers *f*, and rods *b*, substantially as set forth.

6. In a grain-cradle, a tube provided with transverse slots adapted to receive loops or eyes formed on the fingers, in combination 50 with a finger-securing rod extending through the tube, substantially as set forth.

7. In a grain-cradle, an adjusting-bar, *g*, having its edge turned over to increase its strength, and provided with a series of perforations for the attachment of the ends of the fingers, substantially as set forth. 55

8. In a grain-cradle, the combination, with the handle or snath, the adjusting-bar *g*, secured thereto, and the cradle-fingers secured 60 to the adjustable bar, of the bracket *h*, secured to the handle or snath and folded over onto itself to carry one end away from the handle, the free end being provided with a series of holes for the attachment of one end of the adjusting-bar *g*, substantially as set forth. 65

9. In a grain-cradle, the combination, with the fingers adjustably secured to the handle, the handle, and the stay-rods, of the slotted tubes adapted to separate the fingers, the rods 70 *b*, extending longitudinally through the tubes, and the blade bolted to the rods *b*, substantially as set forth.

10. In a grain-cradle, the combination, with a series of fingers secured to the blade and to 75 an adjustable bar attached to the handle or snath, of the stay-rods, substantially as described, adapted to secure the fingers to the handle or snath, substantially as set forth.

WILLIAM BENJAMIN SMITH.
